UNITED STATES PATENT OFFICE.

CHARLES L. HILL, OF ALBERT LEA, MINNESOTA.

TIME-COMPUTING DEVICE.

1,277,723.

Specification of Letters Patent. Patented Sept. 3, 1918.

Application filed December 17, 1917. Serial No. 207,399.

To all whom it may concern:

Be it known that I, CHARLES L. HILL, a citizen of the United States, residing at Albert Lea, in the county of Freeborn and State of Minnesota, have invented certain new and useful Improvements in Time-Computing Devices; and I do hereby declare the following to be a full, clear, and exact description of the invention, such as will enable others skilled in the art to which it appertains to make and use the same.

My invention has for its object to provide an extremely simple and highly efficient computing device for finding the time in months and days within a year limit, that has elapsed since any past date and the current date, or between the current date and some future date, or between any two dates.

To the above end, the invention consists of the novel devices and combinations of devices hereinafter described and defined in the claims.

In the accompanying drawings, which illustrate the invention, like characters indicate like parts throughout the several views.

Referring to the drawings,

Figure 1 is a face view of the invention;

Fig. 2 is a view corresponding to Fig. 1, with the exception that the cover plate is removed and some parts broken away; and

Fig. 3 is a view in section taken on the line 3—3 of Fig. 1.

The numeral 4 indicates a frame having a removable cover plate 5 held in position by upper and lower turn-buttons 6. This cover plate 5 is opaque, except for a quadrant sight opening 7 and a straight sight opening 8, which are transparent. Formed in the frame 4, under the cover plate 5 and at the axis of the sight opening 7 is a large annular recess 9 into which projects, from the frame 4, a pivot pin 10 having rotatively mounted thereon a disk 11. Rigidly secured to the edge of the disk 11, is a radially projecting finger piece 12, by which said disk may be given half rotations in either direction.

Formed in the frame 4, under the cover plate 5, at the left of the recess 9, is a guide channel 13, which extends from the top to the bottom thereof. The frame 4, outward of the guide channel 13, affords a scale bar 14, which extends parallel to said guide channel. Mounted to slide in the guide channel 13, is a movable scale 15, graduated from its top to its bottom and having printed or

otherwise marked thereon the names of the months, towit: January to December, inclusive, reading from the top down.

Marked on the cover plate 5, on a line extending at right angles to the sight opening 8 and through the axis of the disk 11, is an indicator 16 into registration with which any one of the twelve months may be brought by moving the scale 15. This movable scale 15 is moved endwise in the guide channel 13 by a finger piece 17, which works through an opening 18 between the frame 4 and scale bar 14. The peripheral upper edge portion of the disk 11 is graduated into sixty-two divisions, thirty-one of which are indicated by the numerals "1" to "31," inclusive, and afford a movable scale 19. The other thirty-one graduations are indicated by the numerals "0" to "30," inclusive, and afford a movable scale 20. The numerals represented on the two scales 19 and 20 all read in the same direction. To make the two scales 19 and 20 distinctive, the numerals on the latter are preferably in red. By turning the disk 11 with the finger piece 12, the scales 19 and 20 may be moved under the sight opening 7 and the scale 19 may be moved past the indicator 16.

Concentric with the movable scales 19 and 20 and also the sight opening 7, is a quadrant fixed scale 21 graduated into thirty-one divisions, indicated by the numerals "0" to "30," inclusive, printed or otherwise marked on the cover plate 5, inward of the sight opening 7. It is important to note that the zero mark on the fixed scale 21 is directly opposite the indicator 16 and that the numerals read from the left to the right, while the numerals of the coöperating movable scales 19 and 20 read from the right to the left.

The fixed scale bar 14 is graduated from top to bottom and the graduations are indicated by two columns of numerals of two groups each, and both columns of numerals read from the bottom upward. The lower and upper groups of numerals in the right-hand column are indicated by the numerals 23 and 22, respectively, and the lower and upper groups of numerals in the left-hand column are indicated by the numerals 25 and 24, respectively. The numerals in group 23 read "1" to "11," inclusive, and the numerals in group 22 read "0" to "11," inclusive, the zero graduation being directly opposite the indicator 16. The numerals 25

read "0" to "11," inclusive, and it will be noted that the numeral "11" is directly opposite the indicator 16 and the group of numerals 24 read "0" to "10," inclusive. It will thus be seen that the numerals in the left-hand column are spaced one graduation above the corresponding numerals in the right-hand column.

To make the two columns of numerals on the fixed scale bar 14 distinctive, with respect to each other, and associate the same with the two movable scales 19 and 20, the numerals in the right-hand column are black to associate the same with the black numerals of the movable scale 19 and the numerals in the left-hand column are red to associate the same with the red numerals of the movable scale 20. It is, of course, understood that in place of using red and black colors, in distinguishing the two columns of numerals on the fixed scale 14, with respect to each other, and associating the same with the two movable scales 19 and 20, suitable other distinguishing characteristics may be used.

From the above description, it is evident that by operating the finger piece 12, the movable scales 19 and 20 may be oscillated beneath the sight opening 7 to bring certain of the numerals indicated on the fixed scale 21. It is also evident that by moving the finger piece 17 any one of the months, indicated on the movable scale 15, may be brought into registration with the indicator 16. When one of the months indicated on the scale 15 is in registration with the indicator 16, the other months are directly opposite certain of the numerals in the several groups 22, 23, 24 and 25.

In the drawings, the movable scale 15 is in a position which brings the month of November in registration with the indicator 16. It will also be noted that the numeral 14 of the movable scale 19 is in registration with the indicator 16, so that the computing device is set to read "Noyember 14," which is assumed to be the present day. For example, suppose we wish to know how long a note has run, dated July 19th. The first step is to locate the numeral 19 on the fixed scale 21, and radially opposite this numeral is the numeral "25" in the movable scale 20, which, as previously stated, is in red ink to associate the same with the left-hand column of numerals of the same color, including groups 24 and 25 of the fixed scale 14. This numeral "25" of the movable scale 20 represents the intervening fraction of a month in days between July 19th and November 14th.

The next step is to locate the month of July on the movable scale 15 and opposite this month will be found in group 24 the numeral "3" in red. This numeral 3 represents

months between July 19th and November 14th. It will thus be seen that the time elapsed between July 19th and November 14th is three calendar months and twenty five days.

By reference to the drawings, it will be noted that plus signs are marked on the movable scale 15 in the graduations next below the months having 31 days, towit: January, March, May, July, August, October and December, and that the minus sign is marked in the graduations next below the month having less than thirty days, towit: February. The purpose of these plus and minus signs is for use in determining the intervening days between two given dates, when it is desirous of calculating thirty-day months. In the example previously given, the number of days between July 19th and November 14th was three calendar months and twenty five days.

If it is desirous of determining the number of days for the same period, working on the basis of thirty-day months, it will be necessary to add to the total number of days the three extra days included in the months of July, August and October, or in other words, the number of plus signs, indicated between the months of July and November.

The above described device, while extremely simple and of small cost to manufacture, has, in actual usage, proven highly efficient for the purpose had in view.

What I claim is:—

1. A time computing device comprising a frame, two coöperating movable scales, and two fixed scales coöperating one with each of the movable scales, one of said movable scales being graduated to represent the months of a year and the coöperating fixed scale having two distinctive sets of numerals, the numerals of each set being arranged in two groups, each representing intervening months, the other of said movable scales having two distinctive sets of numerals reading in the same direction and each of said sets representing intervening days of a month and the coöperating fixed scale being graduated to represent the days of a month.

2. A time computing device comprising a frame, two coöperating movable scales, and two fixed scales coöperating, one with each of the movable scales, one of said movable scales being graduated to represent the months of a year and the coöperating fixed scale having two distinctive sets of numerals, the numerals of each set being arranged in two groups, each representing intervening months, the numerals in the two groups of each set reading in the same direction, the other of said movable scales having two distinctive sets of numerals successively reading in the same direction and each of said sets representing intervening

days of a month and the coöperating fixed scale being graduated to represent the days of a month.

3. A time computing device comprising a frame, an indicator, two movable scales coöperating with the indicator, and two fixed scales coöperating, one with each of the movable scales, one of said movable scales being graduated to represent the months of a year and the coöperating fixed scale having two distinctive columns of numerals, the numerals of each column being arranged in two groups, each representing intervening months, the numerals of one of said sets reading from the indicator in one direction from "0" to "11" and in the other direction from "11" to "1," the numerals of the other of said sets reading from the indicator in one direction from "0" to "10" and in the other direction from "11" to "0."
4. A time computing device comprising a frame, an indicator, two movable scales coöperating with the indicator, and two fixed scales coöperating, one with each of the movable scales, one of said movable scales being graduated to represent the months of a year and the coöperating fixed scale having two distinctive columns of numerals representing intervening months, the numerals of each column being arranged in two groups, the two groups of numerals at one end of said fixed scale reading away from the indicator and the two groups at the other end thereof reading toward the indicator, the other of said movable scales having two distinctive sets of numerals having two distinctive sets of numerals successively reading in the same direction and each of said sets representing intervening days of a month and the coöperating fixed scale being graduated to represent the days of a month.

5. A time computing device comprising a frame, an indicator, two movable scales coöperating with the indicator, and two fixed scales coöperating, one with each of the movable scales, one of said movable scales being graduated to represent the months of a year and the coöperating fixed scale having two distinctive columns of numerals representing intervening months, the numerals of each column being arranged in two groups, the two groups of numerals at one end of said fixed scale reading away from the indicator and the two groups at the other end thereof reading toward the indicator, the corresponding numerals in opposite groups of the two columns being set one above the other, the other of said movable scales having two distinctive sets of numerals successively reading in the same direction and each of said sets representing intervening days of a month and the coöperating fixed scale being graduated to represent the days of a month.

5. A time computing device comprising a frame, an indicator, two movable scales coöperating with the indicator, and two fixed scales coöperating, one with each of the movable scales, one of said movable scales being graduated to represent the months of a year and the coöperating fixed scale having two distinctive columns of numerals representing intervening months, the numerals of each column being arranged in two groups, the two groups of numerals at one end of said fixed scale reading away from the indicator and the two groups at the other end thereof reading toward the indicator, the corresponding numerals in opposite groups of the two columns being set one above the other, the other of said movable scales having two distinctive sets of numerals successively reading in the same direction and each of said sets representing intervening days of a month and the coöperating fixed scale being graduated to represent the days of a month.

In testimony whereof I affix my signature in presence of two witnesses.
